UNITED STATES PATENT OFFICE.

JONAS NORTHRUP, OF HOPE DALE, MASSACHUSETTS, ASSIGNOR TO WILLIAM F. DRAPER OF HOPE DALE, MASSACHUSETTS; CLARE H. DRAPER AND OLIVER H. LANE EXECUTORS OF SAID WILLIAM F. DRAPER, DECEASED.

FILLING-REPLENISHING LOOM.

973,131.

Specification of Letters Patent Patented Oct. 18, 1910.

Application filed October 1, 1909. Serial No. 529,470.

To all whom it may concern:

Be it known that I, JONAS NORTHRUP, a citizen of the United States, residing at Hopedale, in the county of Worcester and State of Massachusetts, have invented an Improvement in Filling-Replenishing Looms, of which the following description, in connection with the accompanying drawings, is a specification, like letters on the drawings representing like parts.

The invention to be hereinafter described relates to looms and more particularly to looms of the filling replenishing type.

The aims and purposes of the invention are to improve the type of loom specified, so that, subsequent to the transfer of a filling carrier from the source of supply to the weaving instrumentalities, the "filling end" may not be drawn into the shed; and the filling carrier may not cause injury to the warp thread or loom elements in case such carrier fails to be properly placed in the shuttle. These and other features of the invention will best be made clear from the following description and accompanying drawings of one form of means for carrying the same into effect, it being understood that the invention is not limited to the details of structure herein, but is defined in its true scope by the claims.

In the drawings:—Figure 1 is a top or plan view showing sufficient of the filling replenishing side of the loom to make clear the association of the present invention therewith, some of the parts being shown in section; Fig. 2 is a section on the line 2—2, Fig. 1; Fig. 3 is a section on the line 3—3, Fig. 1; and Fig. 4 is a view similar to Fig. 3, showing a modified form of parts.

The loom frame may be of usual or desired form or character, having the breast beam 1, Fig. 1, from which projects the bracket 2, which, if desired, may furnish the supporting means for any preferred character of filling transferring mechanism. In the present illustration the transferring mechanism is designed to transfer a filling carrier 3 from a source of supply to the shuttle 4 when the lay is approximately in its front position, and may comprise a trans- 50 ferrer 5 mounted upon a rod 6 and normally held in raised position by a spring 7, said

transferrer being made operative to transfer a filling carrier by means of the transverse shaft 8 mounted in bearings 9 and having 55 the arm 10 and spring 11; the construction, being such that upon failure of filling from any cause, said train of mechanism will effect a transfer of a filling carrier from the source of supply to the shuttle, as well understood by those skilled in the art. If desired, the transferring mechanism may be substantially as shown and described in my application Ser. No. 516,240, filed September 4, 1909, or it may be of any other character, 65 and since its construction and operation are familiar to those skilled in the weaving art, further description and illustration are unnecessary.

The lay 12, which may be of usual construction, is provided with a shuttle box 13 having a front wall 14, a rear wall 15, a top plate 16, and a binder 17, one wall of the shuttle box, preferably the bottom thereof, being slotted as at 18 for the passage of a 75 filling carrier as it is discharged from the shuttle. These parts, as well as the picker stick 19, the picker 20, the cushion 21 and the binder finger 22 may be of usual or any desired form or character, the general construction of the parts thus far described being such that upon indication of filling failure from any cause, as usual, the filling replenishing mechanism will be caused to act as the lay beats up and transfer a filling carrier 3 from the source of supply to the shuttle 4, the filling carrier previously in the shuttle being discharged through the slot or opening 18 of the shuttle box.

The filling ends 22 leading from the filling carriers 3 in the supply are held at some point, as at 23, Fig. 1, so that when a filling carrier is transferred to the shuttle and the shuttle is picked, the filling end 22, leading from the carrier now in the shuttle, is liable 95 to get into the shuttle box and be drawn into the shed on some subsequent excursion of the shuttle, with the result that imperfect cloth is produced. It may sometimes happen also that the filling carrier may not be 100 properly placed in the shuttle by the trans- ferrer, either because the shuttle is not in proper position to receive the carrier and have its head end 24 engaged by the holding

jaws 25 of the shuttle, or the transerrer may push the carrier too far through the shuttle or possibly not far enough. In any event the filling carrier is liable to have one or the other end thereof projecting from the shuttle, so that when the shuttle is picked the projecting end is liable to engage and tear out the warp threads, as will be readily understood.

10 To avoid the defective actions above indicated and secure a uniform and perfect product, the present invention contemplates means, one form of which will now be described. Secured to the back part of the shuttle box 13, preferably on the top plate 16, is a finger 26, which, for identification, may be termed a filling end director. This director has a slotted foot portion 27 adapted to receive a screw bolt 28 threaded into the 20 top plate 16, Fig. 3, of the shuttle box, whereby it may be adjusted. The director 26 extends above the shuttle box from back to front, and its front end 29 is received by a countersunk portion 30 in the front wall of 25 the shuttle box, the construction being such that as the shuttle is picked, following a replechishment of filling, the filling end leading from the holder 23 to the carrier in the shuttle will pass beneath the end 29 of the 30 director and will be prevented from subsequently passing beneath said end into the shuttle box.

The filling end director 26 has a shoulder 31, which on the forward movements of the lay, after the filling end has once passed under the end 29 of the director, will engage and direct the filling end above the shuttle box; and projecting forward from the front wall 14 of the shuttle box is a filling end 40 guide and support 32 having a shoulder or hook 33 at its end, whereby the filling end may be supported as the lay moves back.

45 Looms of the general character described are or may be provided with filling end severing means adjacent the selvage of the cloth, and to one skilled in the art it will be clear that the devices described will support the filling end leading from the cloth selvage to the filling end holder 23 so that the severing means may better act thereon, and in 50 any event, that the filling end may not enter the shuttle box and be drawn into the shed.

In Fig. 4 the filling end director is shown as of somewhat different form from that of 55 Fig. 3, in that the latter is curved upwardly to provide the shoulder 31, whereas the former is more flat, as at 26*, and has a hook portion 31* to engage the filling end as the lay beats up.

60 The form of the invention illustrated shows the end 29 of the director received in a slot 30 on the top of the shuttle box wall, but obviously this construction may be variously changed so that after the filling end 65 passed to the outside of the shuttle box

it cannot again enter. It will also be noted that, as the lay beats up, the filling end is not prevented from passing above the shuttle box but is rather directed above it by the filling end director.

70 Thus far the filling end director has been described with reference principally to its functional control of the filling end, but it will be noted, Figs. 1 and 2, that the director is disposed near the inner end of the shuttle 75 box and extends as a bridge across the same, the construction being such that should the filling carrier 3 be improperly placed in the shuttle so that one end thereof projects above the same, the director will either cause 80 said projecting end to be depressed as the shuttle passes under it, or will engage said projecting end and cause the shuttle to stop before it enters the shed.

In Fig. 2 the filling carrier 3 is shown as 85 having been pushed too far through the shuttle by the transferring mechanism, so that the head 24 of the carrier failed to be caught by the holding jaws 25. Under such conditions, as the shuttle is picked it will 90 move toward the shed until the head 24 of the carrier engages the wall 34 at the inner end of the slot 18 of the shuttle box, whereupon the tip of the carrier will be raised so that the upper portion will engage the director 26, located adjacent the shuttle box entrance, and the carrier, as a whole, take position transversely through the shuttle, as in Fig. 2, and cause the shuttle to stop. Such stopping point of the shuttle may, if 95 desired, be approximately at the completion of the picker movement, and when the lay beats up, the shuttle being now out of binder control, the usual knock-off mechanism will 100 operate to stop the loom.

105 The knock-off mechanism may comprise the binder finger 22, the dagger rod 35, the dagger 36, and the usual knock-off lever, which, being well understood, needs no further elucidation.

110 Attempt has not herein been made to indicate all the improper positions assumable by the filling carrier in the shuttle, nor the cause therefor, nor have the various actions of the director been set forth for each of 115 these improper positions, because to those skilled in the art it will be apparent that upon such improper positioning of the filling carrier in the shuttle as to cause injury to the warp threads as the shuttle passes 120 through the shed or damage the loom parts, the director will act either to stop the shuttle in its flight or will so far position the carrier in the shuttle that the warp threads will not be injured. If the second of these 125 conditions occur, the filling will be broken either on the first or a subsequent pick and cause the replechishing mechanism to eject the improperly positioned carrier and put in a fresh one.

From the general character of the means described as a good practical form of the invention, it will be noted that upon the pick of the shuttle following filling replenishment the filling end leading from the shuttle will pass between the parts 29 and 30 at the front of the shuttle box and may rest upon the support 32, and as the lay beats up the filling end will ride on the filling end director over the top of the shuttle box and be thus directed out of the path of the picker and shuttle, either of which would cause breakage of the filling end should it be engaged thereby. Thus the filling end, after once passing under the end of the director, is prevented from getting into the shuttle box and yet is permitted to ride freely over the top of the shuttle box supported by the filling end director.

Various changes may be made in the practical form of the invention, it being understood that the invention is generic and contemplates other means than those shown and described.

25. What is claimed is:

1. In a filling replenishing loom, the combination of a lay having a shuttle box, filling replenishing means, and a filling end director comprising a member extending over the top of the shuttle box and having its front end free to permit the filling end to pass to the front of the shuttle box after the action of the filling replenishing means, and to support it above the shuttle box on the forward movement of the lay.
2. In a filling replenishing loom, the combination of a lay having a shuttle box, filling replenishing means, and a filling end director comprising an arm secured at the rear of the shuttle box and having its front end free adjacent the front of the shuttle box to direct the filling end above the shuttle box after the action of the filling replenishing means.
3. In a filling replenishing loom, the combination of a lay having a shuttle box, filling replenishing means, and a filling end director secured to the rear of the shuttle box and extending over the top thereof.
4. In a filling replenishing loom, the combination of a lay having a shuttle box, filling replenishing means, and a filling end director secured to the shuttle box and extending over the top thereof to support the filling end of the active shuttle above the shuttle box as the lay moves with respect thereto.
5. In a filling replenishing loom, the combination of a lay having a shuttle box, filling replenishing mechanism, and a filling director carried by the lay and extending over the top of the shuttle box and having a front portion to engage beneath and to guide the filling end above the same.
6. In a filling replenishing loom, the combination of a lay having a shuttle box, filling

replenishing mechanism, and a finger extending over the top of the shuttle box, the rear portion of said finger being secured at the rear of the shuttle box and the front end being free.

70

7. In a filling replenishing loom, the combination of a lay having a shuttle box, filling replenishing mechanism, and a finger having a filling engaging shoulder and extending over the top of the shuttle box, the rear portion of said finger being secured at the rear of the shuttle box and the front end being free.

75

8. In a filling replenishing loom, the combination of a lay having a shuttle box, filling replenishing mechanism, and a filling end director extending over the shuttle box near its inner portion and secured to the rear portion thereof.

80

9. In a filling replenishing loom, the combination of a lay having a shuttle box, filling replenishing mechanism, and a filling end director extending over the shuttle box near its inner portion and secured to the rear portion thereof, said filling end director having a filling engaging shoulder.

85

10. In a loom, the combination of a lay having a shuttle box, and a filling end director secured to the rear of and extending over the top of the shuttle box, the front end of said filling end director being free and disposed below the top of the shuttle box.

90

11. In a loom, the combination of a lay having a shuttle box, a filling end director secured to the rear of and extending over the top of the shuttle box, the front end of said filling end director being free, and a guard to prevent a filling end passing under said filling end director into the shuttle box.

100

12. In a filling replenishing loom, the combination of a lay having a shuttle box, filling replenishing means, a filling end director to direct the filling end out of the shuttle box after the action of the filling replenishing means, and a filling end support on which the filling end rests extending in front of the shuttle box.

105

13. In a filling replenishing loom, the combination of a lay having a shuttle box, filling replenishing means, a filling end director secured to the rear of the shuttle box and extending over the top thereof, and a filling end support extending in front of the shuttle box.

110

14. In a loom, the combination of a lay having a shuttle box, a finger secured at the rear of the shuttle box and extending over the top thereof, a recess in the front wall of the shuttle box into which the free end of the finger extends to permit the filling to leave but not enter the box, and a filling end support extending in front of the shuttle box.

115

15. In a filling replenishing loom, the

120

125

combination of a lay having a shuttle box, and a finger extending over the top thereof near the inner end of said box substantially at the end of the shuttle picking movement to engage a misplaced filling carrier in the shuttle and prevent injury to the warp threads.

In testimony whereof, I have signed my name to this specification, in the presence of two subscribing witnesses.

JONAS NORTHROP.
